[57] CLAIM

The ornamental design for a bracket for print head, as shown and described.

DESCRIPTION

FIG. 1 is a perspective view of the bracket for a print head showing my new design;

FIG. 2 is a top plan view thereof on a reduced scale with respect to FIG. 1;

FIG. 3 is a front elevational view thereof on a reduced scale with respect to FIG. 1;

FIG. 4 is an end elevational view thereof on a reduced scale with respect to FIG. 1; and

FIG. 5 is a rear elevational view thereof.
